UNITED STATES PATENT OFFICE.

LUTHER D. HASKELL, OF ESSEX, MASSACHUSETTS, ASSIGNOR TO ALBERT R. MacKUSICK, OF BOSTON, MASSACHUSETTS.

BOWLING-ALLEY.

1,026,949.

Specification of Letters Patent.

Patented May 21, 1912.

Application filed January 28, 1911. Serial No. 605,268.

To all whom it may concern:

Be it known that I, LUTHER D. HASKELL, a citizen of the United States of America, residing at Essex, in the county of Essex and State of Massachusetts, have invented new and useful Improvements in Bowling-Alleys, of which the following is a specification.

My invention relates to amusement apparatus, and its primary object is to provide bowling alleys wherein the pins are set upon the players' end of the alley and a cushion secured to the opposite end of the alley, thus requiring the player to direct the ball against the cushion in such manner that its rebound will be in the direction of the pins.

A further object of the invention is to provide a bowling alley which is simple of construction, one which may be readily, quickly and cheaply erected, and one which will afford a high degree of amusement.

The invention consists in a bowling alley comprising a runway having a ball-reflecting cushion at its farther end, and a pin-deck at its nearer end, and having in addition at the nearer end a continuation of the said runway constituting a ball-entry portion extending forwardly in advance of the pin-deck, so that the player may stand alongside said continuation, in front of the pin-deck, and his arm may swing above and along such continuation in delivering the ball, and also so that the ball may be delivered upon such continuation in being projected.

An embodiment of the invention is shown in the drawings, in which latter,

Figure 1 is a top plan view of a bowling alley constructed in accordance with my invention, the middle portion of the structure being broken away. Fig. 2 is a central vertical section therethrough.

Referring to the drawing by reference numerals, 2 designates a table or alley, which may be constructed of any suitable material, and which is provided with a forwardly projecting reduced portion 3. The bottom of the table is covered with rubber or suitable cushioning material 2^a employed with a view of reducing the noise caused by the rolling of the balls. The table or alley is preferably inclined in an upward and rearward direction, the end of the portion 3

being supported by short legs 3^a, while the rear end thereof is supported by somewhat longer legs 4. The table or alley is provided with sides 5 and an end 6, cushions 7 being secured to the inner surfaces of the end 6 and the sides 5. A pin-deck 8 is arranged at the players' end of the table or alley 2 alongside the forward end of the portion 3, as fully disclosed in the drawing. The pin-deck 8 is supported in a horizontal plane and is located between sides 9 and 10 the former of which may be omitted. An end 11 is located in front of the pin-deck. The side 10 is arranged in alinement with the side 5 of the table or alley 2. The side 9 may be used as a shield to prevent a misdirected ball entering onto the pin-deck 8. A pit 12 in rear of the pin-deck 8 is adapted to receive the ball after the same has been bowled. A way 13 extends from the rear end of the table or alley 2 to the pit 12 along the side opposite that on which the entry-portion 3 is located and is adapted to convey a misdirected ball to the pit. A cushion 14 secured to the inner surface of the end 11 is adapted to cushion the force of bowled balls before they drop into the pit 12.

In practice, the usual number of pins *a*, *a*, etc., are set up upon the deck 8 and the player stands in advance of the pin-deck 8 and alongside the portion 3. He occupies a position in which his arm swings above and along the said portion 3 and in projecting the ball may deliver it upon the latter. As will be understood, the player bowls the ball up the table or alley against the cushion 7 in such a manner that it will rebound in the direction of the pins. The rules governing the game are or may be those employed in bowling on alleys of the usual construction. As the pins are arranged adjacent the players' end of the alley, this game requires greater skill than is required in bowling on an alley of the usual construction. Any misdirected ball will fall into the way 13 and be conveyed to the pit 12, from which the player may readily extract the same.

The end 6 of the table is preferably provided with a suitable guard 15, the same extending the entire width of the table and being constructed of wire or the like and operating to prevent the ball from being

accidentally thrown over the end of the table should it be struck extraordinarily hard.

From the foregoing description taken in connection with the accompanying drawing, the construction and mode of operation of the invention should be understood without a further extended description.

Changes in the form, proportions and minor details of construction may be made within the scope of the claims without departing from the spirit or sacrificing any of the advantages of the invention.

I claim:

- 15 1. A bowling alley comprising a runway having a ball-reflecting cushion at its farther end, and a pin-deck at its nearer end, and having in addition at the nearer end a continuation of the said runway constituting a ball-entry portion extending forwardly in advance of the pin-deck so that the player may stand alongside said continuation in front of the pin-deck, and his
- 20

arm may swing above and along the same in projecting the ball, and also so that the ball may be delivered upon such continuation in being projected.

2. A bowling alley comprising an inclined plane runway having a ball-reflecting cushion at its farther end, and a pin-deck at its nearer end, and having in addition at the nearer end a continuation of the said runway constituting a ball-entry portion extending forwardly in advance of the pin-deck so that the player may stand alongside said continuation in front of the pin-deck, and his arm may swing above and along the same in projecting the ball, and also so that the ball may be delivered upon such continuation in being projected.

In testimony whereof I affix my signature in presence of two witnesses.

LUTHER D. HASKELL.
